UNITED STATES PATENT OFFICE.

FREDERIC MORTIMER EMERSON, OF BROOKLINE, MASSACHUSETTS.

CONCRETE-MOLD.

No. 811,135.

Specification of Letters Patent.

Patented Jan. 30, 1906.

Application filed September 8, 1905. Serial No. 377,491.

To all whom it may concern:

Be it known that I, FREDERIC MORTIMER EMERSON, of Brookline, county of Norfolk, State of Massachusetts, have invented an Improvement in Concrete-Molds, of which the following description, in connection with the accompanying drawings, is a specification, like characters on the drawings representing like parts.

This invention relates to a mold which is especially adapted to be employed in building concrete walls; and it has for its object to produce a mold which is adapted to be filled while on the foundation and to hold the concrete until it becomes hardened in the desired form and which is adapted to be readily removed without injury to the molded blocks and be used in a similar way to form another section of the wall. I accomplish this object by the means shown in the accompanying drawings, 20 in which—

Figures 1, 2, and 3 are respectively side, plan, and end views of my improved mold. Fig. 4 is an end view of the mold in the open position. Fig. 5 is a longitudinal sectional view showing a method of using the mold.

As shown in the drawings, the mold comprises a pair of side plates *a b*, which are normally held in parallelism at a suitable distance apart. Said plates are preferably provided with suitable transverse reinforcing ribs *a' b'* on their outer sides, and rigidly connected to said ribs, respectively, are a series of bars or arms *c d*, said arms preferably being made of rigid T-iron and extending vertically above the upper edges of said plates to a suitable distance, as shown, and being arranged in pairs, one directly opposite the other. A pair of locking-levers *e f* are provided for each pair of oppositely-disposed arms *c d*, each of said levers being pivotally connected at one end to the upper end of said arms *c d* and the levers of each pair extending in opposite directions over and past the arm opposite thereto, so that the upper end 40 of each arm will act as a stop to hold the opposite lever in an approximately horizontal position, each pair of levers being pivotally connected to each other by means of pivot-bolts *g*, said pivots being located at points approximately in the vertical plane midway between the adjacent faces of the plates *a b*. Longitudinally-extending rods *h* pass through each lever *e* adjacent their ends, and similar rods *i* pass through the ends of levers *f*, so

that each set of levers may be moved in unison. 55 Links *k* are pivotally connected at each end by pivots *k'* to corresponding brackets *m n*, mounted on the upper edges of the side plates *a b*, said brackets extending upwardly to such an extent that the pivotal points are a short 60 distance above said upper edges, as shown. The length of said links is such that when the levers *e f* are resting on their stops in a horizontal position and the side plates are held parallel the center of each pivot *g* will be in the straight or 65 "dead-center" line between the pivots of the particular pair of levers which it connects. A pair of projecting lugs *p q* are formed integral with brackets *m n* or are otherwise secured to each end of the side plates at the upper edges 70 thereof, said lugs projecting toward each other beyond the inner faces of said plates. A pair of heads *r* are provided, one for each end of the mold, said heads being adapted to fit between said plates when they are in the position of Fig. 1. Holes are bored through the side plates *a b* adjacent their ends, and pins *s* are provided which are adapted to pass through said holes to act as supports for said heads 75 when they are in position between the side 80 plates. A brace or prop *r'* is preferably provided on the outer side of each head, so as to hold the same in a vertical position when otherwise unsupported, and a vertical rib *r''* is preferably provided on the inner side of each head. 85 The inner faces of the plates may be lined with sheet metal to provide a smooth finish, and they are preferably provided with an inwardly-beveled portion at their upper and lower edges, so that the corners of the courses 90 will be beveled when finished. Each plate is provided with a handle *a' b'* at each end, which may be conveniently employed in moving the mold.

When the mold is to be placed in position, 95 the heads are first set on the flat foundation at a suitable distance apart. Then the free ends of the levers are swung upwardly, so that the upper ends of the arms *c d* will be swung toward each other, and the plates will be swung apart about the pivots *k'* as centers. The parts are held in this position by means of a hook *w* or other suitable locking device, said hook being shown as pivoted to rod *h* and adapted to engage the opposite rod *i*. The plates are 100 then lowered at opposite sides of the heads until the lugs *p q* engage the upper ends of the heads, so that the latter support the side 105

plates. The hook m is then released, permitting the plates to swing together against the side edges of the heads, the heads preferably being blocked up slightly, so that they hold the plates high enough to prevent the lower edges of the plates from dragging on the foundation as they are swung against the heads. When the plates have been moved against the edges of the heads, the levers e and f will have swung downwardly, so that their connecting-pivots g will be in the dead-center line, and the arms e , f will act to hold and lock the plates firmly in this position. The mold thus formed is then filled with the concrete, which is allowed to stand until it becomes hardened or stiffened, and then the levers e and f are again lifted, causing the plates a and b to be swung away from the sides of the molded block to such an extent that they may then be readily lifted out of contact therewith without in any way injuring it. The fact that the pivots k' are located above the upper edges of the plates enables the latter to be swung free of the blocks throughout the entire width thereof. The heads may then be easily removed. In practice a suitable number of the molds are provided and a series of blocks of concrete are formed therewith at distances apart which are somewhat less than the length of the mold. Then when the blocks have become hardened so that the molds may be removed the molds are set between the blocks, which have previously been laid so that the side plates bear against the sides of said blocks at their ends.

3. (See Fig. 5.) Before the molds are again placed in position boards are placed on the upper surfaces of the previously-molded blocks, so that when the lugs bear on them in placing the mold in position and in subsequently supporting it when it is being filled the blocks will not be injured if they have not become thoroughly hardened. The spaces between the blocks are then filled with the concrete and allowed to harden. The side plates are of sufficient length to overlap the adjacent ends of the previously-laid blocks, and as the heads will not be used in the second operation the concrete will adhere to the previously-laid concrete and a tenon will be formed which will fit the groove previously formed by the rib r^2 on the inner face of the head, thus making a more rigid connection therebetween. When the side plates are again removed, a continuous course will have been produced. Succeeding courses will then be laid on the first course in a manner which will be obvious, care being taken to alternate the blocks so that the middle of one block will be over the joint between two blocks below. In this manner the walls may be built to any desired height.

As shown, the apparatus is adjusted for a wall of the maximum thickness; but in case a wall of less thickness is desired I provide a series of holes g' in the levers e , f for the pivot

g and corresponding holes k^2 in the links k 65 for the pivots k' , so that the plates may be held closer together. Heads of corresponding widths will in such case be employed.

It will be apparent that the principal force which will be exerted on the connections between the arms c and d and the plates a , b will be adjacent the upper edges of the latter, so that I provide additional securing means, as clips y , at this point between said arms and plates. Said arms and levers will thus act to hold the plates in position even if the outward pressure thereon be excessive.

Having thus described my invention, what I claim as new, and desire to secure by Letters Patent, is—

1. A concrete-mold comprising a pair of side plates pivotally connected adjacent their upper edges to swing to and from each other, arms rigidly connected to said plates and extending upwardly therefrom, two oppositely-disposed locking-levers each pivotally connected at one end to one of said arms and to each other at an intermediate point, substantially as described.

2. A concrete-mold comprising a pair of side plates pivotally connected adjacent their upper edges to swing to and from each other, arms rigidly connected to said plates and extending upwardly therefrom, two oppositely-disposed locking-levers each pivotally connected at one end to one of said arms and to each other at a point approximately midway between said plates, substantially as described.

3. A concrete-mold comprising a pair of side plates, a link pivotally connected at each end to said plates to permit said plates to be swung to and from each other, rigid arms connected to said plates and extending upwardly therefrom, and two locking-levers, each pivotally connected at one end to one of said arms and pivotally connected to each other midway between said arms, substantially as described.

4. A concrete-mold comprising a pair of side plates pivotally connected at their upper edges to swing to and from each other, a pair of heads adapted to be held between said plates, projections on said plates adapted to engage the upper ends of said heads, and means for locking said plates against the side edges of said heads, substantially as described.

5. A concrete-mold comprising a pair of side plates pivotally connected adjacent their upper edges to swing to and from each other, arms rigidly connected to said plates and extending upwardly therefrom, two oppositely-disposed locking-levers each pivotally connected at one end to one of said arms and to each other at an intermediate point, and a stop for supporting said levers in a position in which the pivotal connection therebetween is held at the center line of the pivots of said levers, substantially as described.

6. A concrete-mold comprising a pair of

side plates pivotally connected adjacent their upper edges to swing to and from each other, means for locking said plates in a predetermined position, and supporting-lugs connected to said plates at their upper edges and adjacent each end, and extending toward each other beyond the inner faces of said plates, substantially as described.

In testimony whereof I have signed my name to this specification in the presence of two subscribing witnesses.

FRED. MORTIMER EMERSON.
